[57] CLAIM

The ornamental design for a potted plant hanger or similar article, as shown and described.

DESCRIPTION

FIG. 1 is a left side, top and front perspective view of a potted plant hanger or similar article showing my new design;

FIG. 2 is a front right side elevational view thereof;

FIG. 3 is a rear elevational view thereof;

FIG. 4 is a left side elevational view thereof;

FIG. 5 is a front elevational view thereof; and FIGS. 6 and 7 are respectively top and bottom plan views thereof.

The broken line showing of wall and plant in FIG. 1 is for illustrative purposes only and forms no part of the claimed design.
